CLAIM

The ornamental design for a beverage lid with food container, as shown and described.

DESCRIPTION

FIG. 1 is a top perspective view of a beverage lid with food container.

FIG. 2 is an exploded top perspective view of the design of FIG. 1 showing the manner of assembly of the two parts.

FIG. 3 is an exploded bottom perspective view thereof.

FIG. 4 is a top perspective view thereof, wherein the design of FIG. 1 is shown in a position of use with an unclaimed beverage container, straw, and food container lid.

FIG. 5 is a bottom perspective view thereof.

FIG. 6 is an exploded top perspective view thereof showing the manner of assembly of the design of FIG. 1 with an unclaimed beverage container, straw, and food container lid.

FIG. 7 is an exploded bottom perspective view thereof.

FIG. 8 is a top view of both parts of the design of FIG. 1.

FIG. 9 is a bottom view thereof.

FIG. 10 is a front view thereof.

FIG. 11 is a rear view thereof; and,

FIG. 12 is a left-side view thereof; (the right-side view is a mirror image).

The small circular vent feature drawn in broken line on the central top and bottom surfaces of the beverage lid visible in FIGS. 2, 3, and 6-9 depicts portions of the article that form no part of the claimed design. The broken lines showing a beverage container, straw, and food container lid in FIGS. 4-7 depict environmental subject matter that forms no part of the claimed design.
